UNITED STATES PATENT OFFICE

HELMER N. THUNE, OF CLIMAX, MINNESOTA

TIRE GAUGE

Original application filed July 28, 1927, Serial No. 209,014. Divided and this application filed May 28, 1928. Serial No. 281,308.

The present invention is directed to improvements in tire gauges and is a division of my copending application for tire gauge, filed July 28, 1927, Serial No. 209,014.

5 The invention has for its primary object to provide a novel valve arrangement to control the flow of pressure fluid to the gauge.

Another object of the invention is to provide a device of this character so constructed 10 that it can be used in connection with wheels of various kinds, the construction and arrangement being such that air may be introduced into the tire without operating the gauge, if desired.

15 While the drawings illustrate a preferred embodiment of the invention, it is to be understood that in adapting the means to meet specific needs and requirements, the design may be varied and such other changes in the 20 minor details of construction may be resorted to within the scope of the invention as claimed, without departing from the spirit thereof.

For a full understanding of the invention 25 and the merits thereof, reference is to be had to the following description and the drawings hereto attached, in which,—

Figure 1 is a longitudinal sectional view through the device.

30 Figure 2 is a sectional view on line 2—2 of Figure 1.

Figure 3 is a perspective view of the lever.

Figure 4 is a fragmentary side elevation.

Corresponding and like parts are referred 35 to in the following description and designated in the several views of the drawings by like reference characters.

Referring to the drawings, 1 designates a 40 hollow head having a cap 2 threaded thereon and confining a rubber plate 3 provided with a valve seat 4, and cooperating with said seat is a valve disk 5 having a valve stem engaging lug 6 carried thereby. The head 1 terminates in a hollow neck 7 in which is 45 pivotally mounted a lever 8, said lever having its forward end provided with a head 9 adapted to slidably bear against the disk 5, said head being resiliently maintained engaged upon the disk by the spring 10 which 50 has one end fixed to the lever and its other

end engaged with the interior wall of the head 1.

The neck 7 has a threaded extension 11 protruding therefrom and provided with an axial opening 12 in which is slidably engaged a stem 13, said stem fitting in the opening somewhat close, but not too close, to permit air to pass through the opening.

55 Threaded upon the extension 11 is a coupling 14 having a chamber 15 therein and in which is located a coil spring 16 which engages the valve disk 17 fixed to the lower end of the stem 13, and which serves as a closure for the air entrance end of the opening.

60 A nipple 18 leads from the coupling 14 to which an air conducting hose, not shown, is secured for admitting compressed air to the gauge. The rear end of the neck 7 is provided with an exteriorly and interiorly threaded annulus 19, and having its inner 65 end threaded exteriorly thereon is a barrel 20, while the concentrically arranged tube 21 has its inner end threaded interiorly of said annulus, the annulus maintaining the barrel and tube in spaced relation. A portion of 70 the barrel is shaped to define an indicator 75 22.

The tube 21 has threaded therein the extension 23 of the plug 24, said plug having a threaded periphery 25 for engagement with the tubular member 26 movable in the space 80 between the barrel 20 and tube 21, the tubular member 26 having a cap 27 threaded thereon and provided with a threaded opening 28, the purpose of which will later appear. Graduations denoting pounds pressure are marked 85 upon the tubular member 26, as shown in Figure 4, to cooperate with the pointer 22. A gasket 20' is provided in the outer end portion of the barrel to prevent sediment, grit and moisture entering between the barrel and 90 tubular member 26 and into the gauge.

In the forward end of the tube 21 is mounted a hollow piston 29, the forward end of which is closed by a disk 30 having a seat 31 and with which cooperates a ball valve 32, 95 said ball being confined in the cage 33, there being a cup washer 34 fixed thereto.

An air inlet 35 is formed in the rear wall of the neck 7 to permit air to enter the piston 29 seating the ball valve in the seat 31. Hav- 100

ing its outer end threaded in the opening 28 is a cylinder 36 having slots 37 formed therein and slidable on this cylinder is an outer collar 38 which is connected to an inner collar 39 by a coil spring 40, the collar 38 being fixed to the plunger 41 slidable in the cylinder 36 by a pin 42 which is limited in its sliding movement in the slots 37 of the cylinder 36. The plunger 41 is provided with a pair 10 of resilient arms 43 having latches 44 from their outer ends adapted to meet and be released by the cams 45 mounted in the outer collar 39.

The cylinder 36 is further furnished with 15 a pair of slots 46 in which the latches 44 rest and normally interlock with the rear walls thereof. The inner end of the cylinder has secured thereto a plate 47 having recesses 48 formed in its periphery for passage of air 20 into the cylinder and to permit passage of the cams therethrough.

The plunger 41 bears against the disk 48 carried by the inner end of the stem 49, the 25 outer end of which carries a cup-shaped head 50 which normally closes the outer end of the cylinder 36 and when seated will obviously prevent the entrance of dust, grit and moisture. A coil spring 51 encircles this stem and has its inner end bearing against the plunger 30. 41 and its other end engaged with an annular shoulder 52 formed interiorly of the cylinder.

Encircling the cylinders and collars 38 and 39 is a coil spring 53 which has its outer end engaged with the extension 23 of the plug 24, 35 and has its inner end engaged with the outer end of the coil spring 54 which is of less strength than the spring 53, the inner end of the spring 54 being engaged with the disk 30. Since the spring 54 is of less strength 40 than the spring 53, it will allow the piston to move more for each pound of pressure than the spring 53 would allow it to move. This will allow for singular graduation up to a certain pressure, as the cap 27, which brings 45 the cylinder 36 with it in or out, and the barrel 26 will have to be turned around more for each pound, than when at the higher pressure when the spring 53 takes effect and will have to yield.

The plug 24 is provided with an axial bore 55 in order that the cylinder 36 may slide therein during the adjustment of the gauge. It will be apparent that when the head 1 is engaged with an inflation valve of a tire that the valve stem thereof will engage the lug 6, thus unseating the disk 5 and rocking the lever 8, whereupon the inner end thereof will engage the stem 13 to unseat the valve 17 to permit air to pass through the opening 12 and 60 into the tire. Obviously, when the head is removed from engagement with the tire inflation valve stem, the spring 16 and air pressure provided in the chamber 15 will seat the valve 17 to cut off the air supply.

Assuming that the tire is under-flated and

it is desired to inflate the same to the pre-determined pressure, the cap 27 is rotated which feeds the member 26 and cylinder 36 inwardly or outwardly, owing to its threaded connection with the plug 24, until the desired 70 pounds graduation coincide with the indicator 22. As the air pressure builds up in the tire it will back up into the hollow neck 7 and pass through the inlet 35 and will seat and hold the valve 32 seated, thus exerting pressure upon the piston 29 to force the same outwardly, compressing the springs 53 and 54 until the plate 30 contacts with the outer collar 39 and forces the same outwardly against the tension of the spring 40. As soon as the 80 cams 45 fully engage the latches 44 they will be released and the spring 40 will expand, relieving the pressure against the piston and thereby forcing the collar 38 away from the 85 collar 39. The collar 38 carries with it the plunger 41 which is connected to the collar 38 by pins sliding in the slots 37 of the cylinder 36 and this forces the spring 51 to yield and the plunger pushes the stem carrying the cup shaped head 50 out for free escape of air 90 to atmosphere with a hissing sound to indicate that the proper pressure has been built up in the tire. Quick movement of the piston caused by release of the spring 40 will now cause the valve in the piston to engage the plate 47 of the cylinder and the valve 32 will be suddenly moved to a wide-open position. As the air passes into the cylinder 36 it will exert pressure upon the plunger as it passes 100 thereby, thus aiding the compressing of the spring 51 which is a comparatively weak one, but of sufficient strength to force the plunger 41 and collars 38 and 39 forwardly and reseat the same as soon as the gauge is removed from the tire inflation valve. The springs 53 and 54 will return the piston 29 to its normal position and the stiffness of the spring 40 will move the inner collar inwardly by the spring 51 forcing the plunger 41 inwardly in order 105 that the latches 44 will again snap into engagement with the slot 46 of the cylinder 36. If it is desired to ascertain the air pressure in 110 the tire the head 1 is engaged with the tire valve to open the seat 4, but at a pressure which will not rock the lever 8 sufficiently to open the valve 17. In case the tire has been previously 115 over-inflated the gauge will open to permit the escape of excess pressure. Of course, if it is then desired to inflate the tire the head is pressed with sufficient force upon the tire 120 valve to cause the lever to open the valve.

Having thus described the invention, I claim:

1. An air controlling valve comprising an elongated hollow body having a lateral air inlet at one end and a substantially lateral outlet at the opposite end, a valve normally closing the inlet and provided with a stem extending laterally into the body, and a lever 125 within the body pivoted intermediate its ends 130

thereto, one end of the lever terminating opposite the outlet to be acted upon by the valve stem of the tire or other article to be inflated, the other end of the lever extending across the stem of the inlet controlling valve to unseat the latter, and a spring yieldably retaining the lever in its normal position.

2. An air controlling valve comprising an elongated hollow body having a lateral air inlet at one end and a substantially lateral outlet at the opposite end, a valve normally closing the inlet and provided with a stem extending laterally into the body, a closure for the outlet in said body movable into and out of closing relation to the outlet, and a lever within the body pivoted intermediate its ends thereto, one end of the lever terminating adjacent the outlet to bear against the closure for the outlet and the other end of the lever extending across the stem of the inlet controlling valve to unseat the latter when moved to engage the stem, and a spring yieldably holding said lever in a normal position with the outlet closed.

25 3. An air controlling valve comprising an elongated hollow body having a lateral air inlet at one end and a substantially lateral outlet at the opposite end, and having a lateral extension in line with the inlet, a valve seated on the outer end of the lateral extension and provided with a stem passing loosely through said extension and terminating within the valve body, a chambered coupling fitted to the said lateral extension and formed with a hose receiving nipple, a spring in the chamber of the coupling normally holding the valve seated, and a lever within the body pivoted intermediate its ends thereto, one end of the lever terminating opposite the outlet to be acted upon by the valve stem of the tire or other article to be inflated, and the other end of the lever extending across the stem of the inlet controlling valve to unseat the latter.

45 In testimony whereof I affix my signature.
